Primary Examiner — Paula Allen Greene(74) *Attorney, Agent, or Firm* — Hamre, Schumann, Mueller & Larson, P.C.(57) **CLAIM**

The ornamental design for an eargel for an earphone, as shown and described.

DESCRIPTION

FIG. 1 is a front perspective view of the eargel.
 FIG. 2 is a back perspective view of the eargel.
 FIG. 3 is a front planar view of FIG. 1 thereof.
 FIG. 4 is a back planar view of FIG. 1 thereof.
 FIG. 5 is a left side planar view of FIG. 1 thereof.
 FIG. 6 is a right side planar view of FIG. 1 thereof.
 FIG. 7 is a top planar view of FIG. 1 thereof; and,
 FIG. 8 is a bottom planar view of FIG. 1 thereof.
 The features shown in broken lines depict environmental subject matter only and form no part of the claimed design.

1 Claim, 6 Drawing Sheets---
